AUTOPPOINT COMPANY, OF CHICAGO, ILLINOIS, A CORPORATION OF ILLINOIS

PENCIL

Application filed May 8, 1930. Serial No. 450,747.

Our invention relates to pencils and more particularly to mechanical pencils of a novel construction.

A number of objections have arisen to the common form of mechanical pencil, the most prominent being lack of ease and economy of manufacture, a relatively large number of interfitting parts, and lack of efficient means of securing the tip to the holder or barrel in a firm yet easily rotatable manner.

An object of our invention is to provide a pencil that may be simply and economically manufactured, the tip body and barrel being preferably molded.

15 A further object of our invention is to provide a pencil with a minimum number of parts, thus simplifying the operation thereof, as well as the replacement of the leads by a user.

20 A further object is to provide means comprising stuck out wings or ears on the tip sleeve to provide resilient contact of the tip with the barrel.

A still further object is to provide a molded tip, the molded material being allowed to flow into openings in the sleeve whereby the sleeve and tip body are permanently united in a simple, yet efficient manner.

The invention will be more readily understood by reference to the accompanying drawing, in which

Fig. 1 is a longitudinal sectional view of a pencil constructed in accordance with our invention;

35 Fig. 2 is a cross sectional view taken on the lines 2—2 of Fig. 1;

Fig. 3 is a cross sectional view taken on the lines 3—3 of Fig. 1;

40 Fig. 4 is a cross sectional view taken on the lines 4—4 of Fig. 1;

Fig. 5 is a perspective view of the sleeve in the tip, showing the tip body in section; and

45 Fig. 6 is a sectional view on the lines 6—6 of Fig. 5.

By referring to the drawing, it will be seen that our invention comprises a barrel 10, having a central aperture 11 therein, the upper portion 12 of which is non-circular in cross section, a cap 13 closing the upper end,

and a tip, generally indicated at 14. The tip comprises the sleeve 15 best illustrated in Fig. 5, having an enlarged end portion 16 adapted to retain the writing lead 17 at its point of emergence from the tip. At suitable points in the length of the sleeve we provide the slots 18 for a purpose to be later described. At the upper end of the sleeve we provide the ears 19 formed out of the metal in the sleeve. The ears stand out slightly from the tube 60 and are resilient, and provide resilient frictional contact of the sleeve with the inside wall of the circular opening 11 in the barrel 10.

Located within the sleeve 15 and extending 65 a substantial distance therein is the threaded tube 20 having a continuous spiral external thread, adapted to register with the apertures 18 in the sleeve. The tube 20 rests at the bottom against the conical sides of the tip 70 16 of the sleeve 15 and is secured therein in a manner hereafter to be described. A plunger 21 is provided having cooperative function between the tube and barrel by means of the external threads 22 at the lower 75 end thereof, and the non-circular head 23. The head 23 is adapted to be slidable within the non-circular portion 12 of the barrel.

The tip body 24 is formed by molding the same on to the tip assembly, the body being 80 suitably shaped to conform to the desired contour of the tip, and having the flange 25 overlying the lower end 26 of the pencil barrel. When the body 24 is molded, a portion of the moldable material will be forced into 85 the slots 18 in the sleeve, thus anchoring the threaded tube 20, the sleeve 15, and the tip body 24 together and permanently preventing the separation thereof.

It will thus be seen that we have provided 90 a pencil that is simple in construction, economically manufactured, providing an efficient resilient contact of the sleeve inside the body, and a large bearing surface at the lower end of the barrel, as well as an integral tip 95 assembly, the various parts of which are simply and economically joined together.

In operation, assuming a lead 17 in place as shown, in Fig. 1, the tip assembly including the plunger may readily be inserted into 100

the barrel opening, the head 23 of the plunger fitting into the non-circular recess. Thereafter by simply rotating the tip and holding the barrel, or vice versa, the plunger, 5 cooperating with the threaded tube, will advance therein forcing the lead out. Obviously the tip can be replaced or removed in any position of adjustment of the parts.

Obviously modifications may be made 10 within the skill of the mechanic, and we do not wish to be limited excepting as indicated in the appended claims.

We claim:

1. In a pencil of the type in which the contained lead advancing mechanism is actuated 15 by rotation of the tip portion relative to the body or barrel, the combination of a sleeve projecting axially through the tip portion and terminating in an exterior lead guiding portion, a threaded tube confined within the sleeve, a tapered non-metallic body of material overlying the sleeve and constituting the means for defining the contour of the tip portion, and means providing a mechanical connection between the sleeve and the non-metallic body of material to prevent relative rotation.

2. A pencil as characterized in claim 1, in 20 which the sleeve is provided with an opening 30 and the non-metallic material projects into said opening and serves to bind the parts together.

3. A pencil as characterized in claim 1, in 35 which the sleeve has a struck out wing adapted to provide frictional resistance to turning of the tip in the body.

4. In a pencil of the type in which the contained lead advancing mechanism is actuated 40 by rotation of the tip portion relative to the body or barrel, the combination of a sleeve embedded and anchored in a tapered body of non-metallic material, said sleeve having a portion projecting rearwardly beyond the 45 tapered body and adapted to project into the pencil body, said rearwardly projecting portion having a wing struck out to provide frictional resistance to turning of the tip portion in said body, a threaded tube cooperating with the sleeve, and means for securing the tube to the sleeve.

In testimony whereof we have affixed our signatures.
